DESIGN FOR A COMBINED PAINT RECEPTACLE HOLDER AND STIRRER

John C. Kelly and Earl R. Brazie, Owosso, Mich.

Application June 5, 1942, Serial No. 107,138

Term of patent 7 years

To all whom it may concern:

Be it known that we, John C. Kelly and Earl R. Brazie, both citizens of the United States and residents of Owosso, in the county of Shiawassee and State of Michigan, have invented a certain new, original, and ornamental Design for a Combined Paint Receptacle Holder and Stirrer, of which the following is a specification, reference being had to the accompanying drawing, forming a part thereof.

In the drawing:

Fig. 1 is a front elevational view of a combined paint receptacle holder and stirrer showing our new design.

Fig. 2 is a top plan view thereof.

Fig. 3 is a side elevational view thereof.

What we claim is:

The ornamental design for a combined paint receptacle holder and stirrer, as shown.

JOHN C. KELLY.
EARL R. BRAZIE.
